C. W. BURKHEAD,
EXTENSIBLE METALLIC WINDOW SCREEN,
APPLICATION FILED JUNE 7, 1913.

1,158,440.

Patented Nov. 2, 1915.

UNITED STATES PATENT OFFICE.

CHARLES W. BURKHEAD, OF CINCINNATI, OHIO, ASSIGNOR TO BURKHEAD METAL WORKING COMPANY, OF CINCINNATI, OHIO, A CORPORATION.

EXTENSIBLE METALLIC WINDOW-SCREEN.

1,158,440.

Specification of Letters Patent. Patented Nov. 2, 1915.

Application filed June 7, 1913. Serial No. 772,257.

To all whom it may concern:

Be it known that I, CHARLES W. BURKHEAD, a citizen of the United States of America, and a resident of Cincinnati, in the county of Hamilton and State of Ohio, have invented a certain new and useful Improvement in Extensible Metallic Window-Screens, of which the following is a specification.

This invention relates to window-screens that are used in adjustably and detachably connected pairs so as to adapt them for sliding engagement with each other to suit varying widths of windows, and the object of the invention is to provide a pair of corresponding metallic-frame screens duly connected together by means of elongated key-hole slots in the upper and lower frame-bars and laterally-projecting tongues or lugs that are adapted to engage said elongated key-hole slots whereby the two screen-members are detachably and adjustably united for longitudinal sliding-engagement with each other and thus suited to varying widths of window-openings and making snug or close joint with both sides and bottom of the window-frame as well as with the bottom of the window-sash that rests upon the top bars of both said screen-members in order to effectually shut out flies or other insects from the interior of the building.

The specific features of the invention will be fully hereinafter described in detail and then particularly pointed out in the claims.

In the accompanying sheet of drawings, Figure 1 is an elevation of one of the screen-members showing the engaging-face thereof which is a counterpart of the companion screen-member that is adjustably used therewith in a window-opening; Fig. 2, a fragmentary section, taken on the dotted-line α , α , of Fig. 1, but on a somewhat larger scale and showing the locking-tongue together with one end of the elongated key-hole slot; Fig. 3, an elevation of one corner of the screen-member shown in Fig. 1, but on a somewhat larger scale; Fig. 4, a view similar to Fig. 3, but showing a modified form of locking-tongue; Fig. 5, another view similar

to Figs. 3 and 4, but showing a form that is a slight but not a material modification of Fig. 4; and Fig. 6, a transverse section taken on a horizontal line with the interlocking parts of a pair of screen-members.

1 indicates the upper horizontal frame-bar; 2 the lower horizontal frame-bar; 3 one of the vertical end or side bars; and 4 the other vertical end or side bar of a rectangular metallic window-screen, which is the preferred type of screen to which my invention herein is particularly intended or applicable.

1^a and 2^a are lateral extensions of the frame-bars 1 and 2, provided for the purpose hereinafter named.

5 indicates the ordinary mesh or screen wire whose edges are duly held or clamped in the said four members or bars 1, 2, 3 and 4, but not in the extensions 1^a and 2^a, of the screen-frame, each of such members or bars being of U-shape cross section the latter as best seen in Fig. 2 in connection with the horizontal extension 2^a. A spacing-strip 6 is used in both of the horizontal extensions 1^a and 2^a, also as best seen in said Fig. 2.

The upper and lower screen-bars 1 and 2 are each provided with an elongated key-hole slot 7 that begins adjacent the opposite ends of the vertical side-member 3, as shown at the expanded openings or orifices 8 in Fig. 1, the opposite ends of said slots 7 terminating within the extensions 1^a and 2^a, respectively, at a suitable distance beyond the opposite ends of the vertical side-member 4 to provide for an intervening laterally-extending tongue or lug 9 in the extensions 1^a and 2^a of the metal frame-bars 1 and 2, respectively, between the closed ends of the slots 7 and the extreme outer ends of said extensions of the horizontal frame-bars 1 and 2.

The laterally-extending tongues or lugs 9 are preferably made integral with the metal bars 1 and 2, being duly pressed or cut out of the metal by means of suitable dies in one leg or limb of the U-shape bars 1 and 2, and are preferably provided with a longitudinal rib 10 to impart stiffness and

strength thereto, such ribs 10 being made by the dies at the time of making the tongues or lugs 9.

In order to form an adjustable or extensible screen for use in windows of various widths two of the screens just described are used and interlocked by means of the engagement of the laterally-extending tongues or lugs 9 with the key-hole slots 7, the 10 tongues 9 having round or enlarged heads that are adapted to pass into the openings 8 of the key hole slots 7 and thence further pass into the space 11 provided between the limbs or legs of the horizontal U-shape upper and lower members 1 and 2 of both screens. The body or narrow portion of the tongues or lugs 9 is of a width slightly less than that of the key-hole slots 7 so that the tongues can ride or slide freely within said 15 slots and back thereof in the adjustment of one screen-member along the other for effectually closing the window-opening against the entrance of insects. In Fig. 2 I have shown how far the tongues or lugs 20 9 extend outwardly from the face of the upper and lower bars 1 and 2, (bar extension 2^a being, of course, the only one shown in this view,) and the distance between said tongues and bars being slightly greater than that of 25 the thickness of the metal so that the head of each tongue shall slide freely within the space 11 and without too intimate frictional-contact of the engaging faces of the upper and lower bars of the companion screen-members that form the adjustable screen.

In Figs. 1 and 3 I show the tongues or lugs as having circular heads, which form is well adapted to the purpose of interlocking the two sliding screen-members, but in Figs. 4 and 5 I show tongues that have rectangular heads whose engaging surface at either side of the elongated slots 7 is greater than that of said circular form and thereby requires like rectangular entrance-orifices in 45 the slots 7. The form of tongue shown in Fig. 4 is practically T-shape, with its head extended free from the horizontal frame-bar extension, the same as shown in Fig. 2, but the tongue seen in Fig. 5 has a rectangular formation made transverse in the metal that is cut and pressed outwardly from the extension 1^a of bar 1 and held integral thereto by means of the ligament 12. The forms of interlocking-tongues shown in Figs. 4 and 5 50 are each provided with ribs 10, the same as those shown in connection with the tongues seen in Figs. 1, 2 and 3, and for a like reason.

The form of interlocking device shown herein is of an extremely simple and inexpensive nature and is very readily manipulated, both in connecting the two screens for use and for parting them when it is desired to remove them for either storage or shipping. The fit of the two screens is such that 55 a close joint is provided around the edges

thereof, both marginal and internal, the latter being those between the opposite ends of the two screens when in connected position for use. The extensions 1^a and 2^a provide for the full capacity of each screen unit or frame, so that when both screens are duly connected together they can be spread outwardly in opposite directions longitudinally until their respective bars 4 come in vertical contact and alinement at the perpendicular center of the window-opening, imparting greater strength and rigidity at the screen center and a much better appearance to the eye. 70

I claim:—

1. An extensible or adjustable window-screen comprising two screen-members each of which is provided with a rectangular sheet-metal frame and a wire-mesh whose edges are secured in said frame, an elongated key-hole slot made in the engaging-face of the horizontal bars of each of said frames, and an integral, laterally-projecting tongue or lug provided at the narrow or unexpanded end of each key-hole slot and 90 adapted to engage the adjacent corresponding key-hole slot through its expanded or enlarged end in the sliding-attachment or interlocking-engagement of the said two screen-members for detachably and adjustably supporting the extensible-screen in a window-frame. 95

2. An adjustable or extensible window-screen comprising a pair of corresponding screen-members each of which is composed of a pair of horizontal bars and a pair of vertical side-bars that connect the opposite ends of said horizontal bars to form a rectangular sheet-metal frame, a wire-mesh whose edges are secured in said bars of each metal frame, an elongated slot provided in the engaging-face of each of said horizontal bars and having an enlarged or expanded inlet and outlet opening at one end thereof, and an integral, laterally-extending tongue 100 or lug provided in the said engaging-face of each horizontal bar at the opposite, narrow or unexpanded end of each slot and adapted to engage a companion enlarged inlet and outlet opening leading to the space in each 105 horizontal bar back of the slot therein and having a laterally-extended head or formation that is adapted to interlock with the slotted portion of the contacting-faces of the companion screens. 110

3. An extensible or adjustable window-screen comprising a pair of corresponding, rectangular screen-members each of which has a pair of sheet-metal side-bars, a pair of sheet-metal horizontal bars connecting said 115 side-bars and having alined upper and lower lateral-extensions at one end thereof, a wire-mesh having its edges clamped in said frame-bars, an elongated key-hole slot made in the engaging or contacting face of each of 120

said horizontal bars and their said upper and lower lateral-extensions, and an outwardly-projecting tongue provided at the end of the narrow or unexpanded end of each key-hole 5 slot and adapted to engage the adjacent key-hole slot through its expanded or enlarged end in the interlocking and sliding engage-

ment of said two screen-members for detachably and adjustably supporting the extensible screen in position for use.

CHARLES W. BURKHEAD.
